UNITED STATES PATENT OFFICE.

CIRILLO DI PIETRO AND DANIEL M. COLUCCI, OF WATERBURY, CONNECTICUT.

SIGNAL FOR GASOLINE TANKS.

Application filed May 2, 1923. Serial No. 636,136.

To all whom it may concern:

Be it known that we, CIRILLO DI PIETRO, a citizen of the United States, and a resident of Waterbury, county of New Haven, and State of Connecticut, and DANIEL M. COLUCCI, a citizen of Italy, and a resident of Waterbury, county of New Haven, and State of Connecticut, have invented certain new and useful Improvements in Signals for Gasoline Tanks, of which the following is a specification.

This invention relates to automobile signals, and more particularly to an alarm device for warning the driver of an automobile when the fuel in the supply tank has become nearly exhausted.

One object of the invention is to provide an alarm device for use upon automobiles, to indicate when the level of the gasoline in the supply tank has fallen to a predetermined point.

A further object is to provide a device of the above nature having means operated by a float in the gasoline tank for opening communication between a source of vacuum and an alarm whistle, when the amount of gasoline has reached the predetermined minimum, and also having means whereby the whistle may be silenced whenever desired.

A further object is to provide a gasoline-level alarm device of the above nature, which will be simple, cheap to manufacture, reliable, efficient, and which may be installed in any type of motor vehicle.

With these and other objects in view, there has been illustrated on the accompanying drawing one form in which the invention may be conveniently embodied in practice.

Fig. 1 represents a side view, partly in section, of the gasoline-level alarm system as it appears when installed on an automobile.

Fig. 2 is a sectional view of the device taken on a plane at right angles to the view shown in Fig. 1, and on a considerably larger scale.

Fig. 3 is a top sectional view on an enlarged scale, of the valve chamber, taken on the line 3—3 of Fig. 2.

Referring now to the drawings in which like reference numerals denote corresponding parts throughout the several views, the numeral 10 indicates a gasoline tank adapted to be located in any convenient position upon an automobile, preferably at the rear thereof. The tank 10 is provided at its top with an annular raised section 11, preferably circu-

lar in shape, said raised section having a concentric aperture 12. Mounted on the annular raised section 11 and secured thereto by bolts 13, is an annular ring 14, said ring having a rib 15 extending upwardly therefrom. The inner edge of the ring 14 is threaded at 16 to receive a threaded depending flange 17 of a valve head 18. The valve head 18 has its edge 19 adapted to 65 overlie the rib 15 so as to produce a rigid interlocking structure.

The valve head 18 has a narrow interior vertical chamber 20, as clearly shown in Fig. 2. This chamber 20 is in open communication with a pair of pipes 21 and 22 which pass through the top of the valve head 18. The vertical chamber is provided with a round socket 23 at its top which is adapted to form a seat for the top of a relatively long 70 plunger 24, of larger diameter than the width of said vertical chamber, said plunger being slidably fitted within a depending neck portion 25 of the valve head 18.

The lower end of the neck portion 25 80 is provided with a transverse aperture 26 within which a pin 27 fixed to the rod 24 is adapted to have a limited up-and-down movement. The lower end of the valve rod 24 is screwed into a hollow collar 28, said 85 collar being united to the top of a hollow float 29 in any suitable manner, as by soldering. The float 29 is open at the bottom, and is adapted to contain a sufficient quantity of air to cause the float to exert a continuous upward pressure upon the valve rod 24. The top of the valve rod 24 will thus be held in the socket 23 except when the level of the gasoline has fallen below the danger point, at which time the rod will 90 move down out of its socket 23, and communication will be opened between the pipes 21 and 22 through the narrow passage 20.

The pipes 21 and 22 are connected at their upper ends to elbows 30 and 31 respectively. Connected to the elbow 30 is a whistle-operating pipe 32, which extends forwardly under the body of the car, and rearwardly through the dashboard 33 to a vacuum-operated whistle 34 located on the instrument board 35. A valve 36 operated by a handle 37 is also provided, by means of which the whistle may be connected or disconnected as desired. The elbow 31 also has connected thereto a pipe 38 which passes forwardly 105 under the body of the car, said pipe then extending upwardly under the engine hood 110.

to a T connection 39. The T connection 39 is also connected to the intake manifold 40, and to a pipe 41 leading rearwardly to the usual vacuum feed tank 42.

5 In operation, when the level of the gasoline in the tank has fallen below the predetermined point, the top of the rod 24 will move out of its socket 23. This will then open communication through the narrow 10 chamber 20 between the vacuum pipe 22 and the pipe 21. Air will then be sucked through the pipe 32 and the whistle will produce a loud noise. The sound of the whistle will indicate to the driver that the level of the 15 gasoline has fallen to the danger point, and will warn him to stop at the next filling station to have the tank refilled. In order to silence the whistle, it will only be necessary for the operator to reach under the instrument board 35 and turn the handle 37 until the valve 36 is closed. After the tank 20 has been refilled, the operator may again open the valve 36 to restore the parts to their original working condition.

25 While there has been disclosed in this specification one form in which the invention may be embodied, it is to be understood that this form is shown for the purpose of illustration only, and that the invention is 30 not to be limited to the specific disclosure, but may be modified and embodied in various other forms without departing from its spirit. In short, the invention includes all the modifications and embodiments coming 35 within the scope of the following claims.

Having thus fully described the invention, what is claimed as new, and for which it is desired to secure Letters Patent, is:

40 1. In an alarm device for warning the driver of a motor vehicle when the fuel in the supply tank has become nearly exhaust-

ed, a casing having a flange for attachment to the edge of an opening in the top of the tank, said casing having an interior passageway communicating at one end with a 45 source of vacuum and at the other end with an air-operated signal, a plunger extending into said casing at right angles to said passageway and extending therethrough, a float directly connected to the lower end of 50 said plunger, the top of said plunger being adapted to normally close said passageway and being adapted to fall and open communication between the ends thereof when the level of liquid in said tank has 55 dropped to a predetermined point.

2. In an alarm device for warning the driver of a motor vehicle when the fuel in the supply tank has become nearly exhausted, a casing having a flange for attachment 60 to the edge of an opening in the top of the tank, said casing having an interior horizontal passageway communicating at one end with a source of vacuum and at the other end with an air-operated signal, a 65 plunger extending into said casing at right angles to said passageway and extending therethrough, said passageway having a socket in its upper surface adapted to form a seat for the upper end of said plunger, a 70 float directly connected to the lower end of said plunger, the top of said plunger being adapted to normally close said passageway and being adapted to fall and open communication between the ends thereof when the 75 level of liquid in said tank has dropped to a predetermined point.

In testimony whereof, we have affixed our signatures to this specification.

CIRILLO DI PIETRO.
DANIEL M. COLUCCI.
